SMOKE, FUME, AND GAS EJECTOR
APPARATUS

Roy B. Farrell, Buffalo, N. Y.

Application July 24, 1944, Serial No. 546,381

4 Claims. (Cl. 98—43)

1

This invention relates to fire fighting apparatus and has particular reference to means for combating the smoke nuisance or hazard incidental to many conflagrations.

In entering a burning building the firemen are frequently confronted with dense clouds of smoke billowing forth from a room, to such an extent as to make it exceedingly difficult to approach and sometimes to locate the area of combustion. This not only results in a costly delay but it also places the lives in jeopardy because of the difficult situation.

The object of the present invention is to provide a fire fighting apparatus which is practical and efficient in operation and which will enable an expeditious change of the air or gas content of a room within a brief interval of time so as to enable a prompt and safe entry onto the premises as well as a quick suppression of the fire.

A further object of the invention is to provide an airflow apparatus designed to be adapted to and operated by the well known water line of fire fighting equipment and thus avoid the necessity of reliance upon an outside source of power for its effective operation.

Furthermore, the invention has for its aim to provide an air exchange device in which the undesirable air or gas content of a building will be thoroughly commingled with a spray of water in a manner to effect a safe removal of the gas and smoke against becoming a nuisance.

Again the invention has for its object to provide a gas remover designed for attachment to the fire hose for use in removing dangerous fumes and vision obscuring smoke from a building as well as to enable the introduction of fresh air thereinto for the safety of the lives involved as well as for the expeditious extinguishment of the conflagration.

In the drawing:

Fig. 1 is a longitudinal sectional view, in fragment, showing the fire fighting apparatus embodying the present invention;

Fig. 2 is a front elevation of the apparatus or device, with portions of the shield broken away;

Fig. 3 is a plan or edge view of the device;

Fig. 4 is a sectional view through a modified form of the invention;

Fig. 5 is an elevation in fragment of a conduit or tube employed for increasing the efficiency of the apparatus; and

Fig. 6 is a diagrammatic view depicting a practical application of the apparatus.

Referring more particularly to the drawing, the numeral 1 designates a drum-like housing

2

which preferably is of cylindrical formation and is opened at its opposite ends to provide a mixing chamber 2. Suitably supported by a bracket 3 within the mixing chamber 2 is an axially disposed nozzle 4 which has a head 5 designed to discharge a conical spray of water, as indicated at 6, in an axial direction. This spray of water is designed to flare outwardly and impinge against the inner surface of the mixing chamber under a forward impetus toward the discharge end 7 of the chamber so as to induce air inflow through the front end or inlet opening 8. This impingement of the water further tends to break up the liquid particles toward an atomizing action for thoroughly saturating and washing the smoke when brought into contact therewith so that the result is a liquid spray discharge impregnated with the smoke constituents.

The cone forming head 5 may be adjusted, if desired, by mounting the same on a threaded stem 9 which finds support in the bracket 3 or the adjacent nozzle body 4. The included angle of flare for greatest efficiency has been found in practical use to be approximately 60° since the conical liquid spray at this angle will impart the desired forward impetus to the body of mist, which serves in the capacity of a liquid or fluid piston moving toward the discharge end 7 of the mixing chamber 2, for effecting a maximum displacement of gas through the inlet 8. The diameter of the mixing chamber may be sufficiently large to satisfactorily change the entire gas content of a room in the shortest interval of time, those having been found practical in actual tests having diameters of approximately 14 to 22 inches. The spray or atomizing nozzle 4 is located adjacent the inlet end of the chamber so that the flaring cone of water will impinge against the interior wall of the chamber slightly beyond the halfway mark or at a point to provide a sufficient length of travel of the piston of spray within the mixing chamber for effecting the desired air displacement.

The spray producing nozzle 4 is provided with a pipe extension 10 terminating in a branched or T-coupling, as indicated at 11, each branch being provided with a check valve 11' for closing under the water pressure when the companion branch is connected to the usual fire hose 12. Thus, the branches are selectively connectible, as by means of the usual threaded coupling ring or fitting 13, to the fire hose or water line.

The device is provided with a suitable mount, preferably in the form of a shield 14, the same having suitable handles 15 to facilitate its car-

riage and to enable the firemen entering the room behind the device as a protection. The shield may have extensible wings 16 hingedly connected for folding against the housing 1, as depicted in Fig. 3. This will permit ready storage of the device on the fire engine or truck, the wings being supported in extended position by suitable means such as hooks 17 which are adapted to engage over a fixed part on the center or body section 14.

Referring particularly to Fig. 6 which shows a building or room 18 having a fire indicated at 19, two of the fire fighting apparatuses are disposed in the opposing window openings 20 and 21, the apparatus 22 in window 20 serving to eject the smoke from the fire while a second apparatus 23 may be disposed in the window opening 21 for injecting fresh air into the room 18 and thereby driving out the injurious fumes and gas through the remote window openings 20 and 24. While the two apparatuses may be used in such co-operating relation, if desired, it is intended to use them singly since the air displacement is so large, by reason of the spray piston, that one apparatus alone will suffice to readily change the gaseous content of the room in a very brief interval of time.

The practical illustration shown gives the alternate uses of the apparatus, either as a smoke ejector or as a fresh air injector. It is made portable by the handles 15 so that the fireman may carry the device in front of him and use it as a fresh air injector as he enters the smoke-filled room through the doorway 25.

In use, it is only necessary that the firemen place the device either in the position indicated at 22 where it will be used as a smoke ejector for quickly clearing the room or building of the obnoxious gases or he may place it to function as a fresh air injector, as shown at 23. The shield 14 with its extensions 16 are of sufficient size to provide a mount for the apparatus which will either fit within or overhang the window opening, suitable means (not shown) being employed to interlock the shield in position. The fire hose which is usually provided with the shut-off valve 26 will enable the ready attachment of the hose to the apparatus, either to the right hand or the left hand branch coupling 13, while the unused branch will be closed by the check valve 11.

The mixing chamber 2 may be extended by means of a telescopic section 28 on the housing 1. By extending this section, the mixing chamber will, in effect, be lengthened for carrying the smoke-saturated spray discharge from the room; or if desired, a collapsible flexible tubing or conduit 29 may be substituted therefor and attached to either the inlet end or the discharge end of the mixing chamber. When attached to the inlet end it may be used for conveying fresh air through a smoke-filled compartment in the building to the mixing chamber without contamination. When attached to the discharge or outlet end 9 the spray discharge will be carried through another room without contaminating the air therein and finally discharged through a window opening therein. This gives a flexibility of use and adaptation for the apparatus so as to enable its employment under a most varied usage.

In some fields of use it may be desirable to provide a twin device as shown in Fig. 4 wherein the nozzles 4' are of branch formation so as to produce oppositely directed cones of spray, as

indicated at 6', for discharging in opposite directions within the T-shaped mixing chamber 2'. The housing 1' has a fresh air inlet 7' entering the chamber between the oppositely moving piston forming sprays which latter discharge through the outlet openings 9'. The fire hose with its high pressure water stream may be selectively connected to one or the other of the two branches 11' as in the case of the embodiment shown in Figs. 1, 2 and 3. The displacement of this modification will be enlarged and thereby increase the velocity of the air stream entering the inlet 7'.

The apparatus is of simple and durable construction. Its operating power is derived from the fire fighting equipment. When used as a smoke ejector the smoke is intermingled with the spray in such a manner that the resultant discharge is in the form of a shaft of mist or an atomized spray, the cross sectional shape of the discharging body of spray being imparted by the discharge orifice 7. The device is readily mountable within a window or door opening where it may be firmly anchored. The twin arrangement shown in Fig. 4 provides an arrangement wherein one spray is caused to react against the companion spray toward the stabilization of the apparatus when in use.

By reason of the piston forming spray a relatively large mixing chamber may be employed to augment the air displacing capacity of the device and thereby make it practical for effecting a quick change of the air content in a room or building. This will expedite the firemen's work in safely combating the flames or conflagration with a minimum property damage. In practical demonstrations the air displacement has varied in accordance with the diameter of the mixing chamber as well as the pressure on the water line. For example with a 22" drum at hydrant pressure, which is about 55 pounds, approximately 5,000 cubic feet of air per minute at 70° F. were displaced, while under a 200 pound engine pressure on the water spray, approximately 11,750 cubic feet of air per minute were displaced. The reading on the U-tube (water) increased from $\frac{1}{2}$ " to $2\frac{1}{2}$ ". With a nozzle having an orifice of $\frac{3}{4}$ inch diameter operating in the 22 inch cylinder the effective area of the cylinder with respect to the effective area of the nozzle is substantially in the ratio of 861 to 1; with a 14 inch cylinder and a nozzle having an orifice of $\frac{1}{2}$ inch diameter the ratio will be approximately 779.7 to 1. With these approximate ratios the greatest efficiency is secured. Substantial variations in this ratio, as well as substantial variations in the included angle of the spray cone will change the efficiency in that it may require a larger pump, more power to drive the same, and a greater back pressure or suction generated. With a mixing chamber having a 14" diameter the air displacement under the same engine pressure displaced 4,200 cubic feet of air per minute. The air exchange device is not confined to fire fighting apparatus, but is applicable to other fields of use where the circulation of air is to be accomplished in a practical and expeditious manner.

Furthermore, the device actually adapts the usual fire hose, when equipped with a spray type nozzle, as a medium for removing the objectionable smoke and gases from a building. For this reason the bracket 3 may detachably support the nozzle 4 so that the latter may be removed and used alone with the fire hose independently of the housing 1. Because of its portable charac-

ter the device after attachment to the fire hose may be carried about and maneuvered to the best advantage in suppressing the fire, the shield serving to baffle the heat from direct contact with the firemen.

It will be understood further that the apparatus and system described and shown herein is merely illustrative of the inventive principles involved, which may be applied to other physical embodiments without departing from the scope and spirit of the invention claimed.

What is claimed is:

1. A fire fighting apparatus of the class described comprising a mixing chamber having an inlet and an outlet, a spray forming nozzle disposed axially within the chamber and arranged to produce a spray of liquid flaring outwardly against the interior wall of the chamber under a forward impetus toward the outlet end of the chamber, and means for connecting the nozzle to a fire hose for receiving water therefrom to produce the piston forming spray, said means comprising branched couplings selectively engageable with the fire hose, with a check valve in each coupling adapted to close the same under the water pressure delivered by the hose when engaged with the companion coupling.

2. A fire fighting apparatus of the class described comprising a mixing chamber having an inlet and an outlet, a spray forming nozzle disposed axially within the chamber and arranged to produce an atomized spray of liquid flaring outwardly against the interior wall of the chamber to provide a body of mist moving toward and discharging from the outlet end of the chamber, means for connecting the nozzle to a fire hose for receiving water therefrom to produce the body forming spray, and a mount for the chamber to enable placement of the same in an opening in the wall of a building, said mount being provided with handle means by which it may be carried about, said connecting means comprising branched couplings selectively engageable with the fire hose and having valve means responsive to the liquid pressure for closing the unconnected coupling.

3. A blower comprising a cylinder of substantially uniform cross sectional area throughout its length and open at each end, a relatively small nozzle connected to a high pressure water line and located centrally of the cylinder adjacent one of its open ends, said nozzle having an annular spray opening disposed centrally of the nozzle and the cylinder for forming and directing a hollow cone of water under high pressure directly against the inner wall of the cylinder adjacent its opposite open end, the effective area of the cylinder with respect to the effective area of the nozzle being substantially in the ratio of 800 to 1,

whereby the water of said cone in rapidly moving from the nozzle to the inner wall of the cylinder forms a broken spray the globules of which move divergently and permit slippage of air therebetween thereby reducing the vacuum effect at the inlet end of the cylinder and upon impingement upon the inner wall of the cylinder the globules of the spray further disintegrate to form a mist, the rapidly moving globules of the spray and the mist combining to move a large volume of air through the cylinder.

4. A blower comprising a cylinder of substantially uniform cross sectional area throughout its length and open at each end, a relatively small nozzle connected to a high pressure water line and located centrally of the cylinder adjacent one of its open ends, said nozzle having an annular spray opening disposed centrally of the nozzle and the cylinder for forming and directing a hollow cone of water under high pressure directly against the inner wall of the cylinder adjacent its opposite open end, the effective area of the cylinder with respect to the effective area of the nozzle being substantially in the ratio of 800 to 1, and the included angle of the cone of spray being substantially 60°, whereby the water of said cone in rapidly moving from the nozzle to the inner wall of the cylinder forms a broken spray the globules of which move divergently and permit slippage of air therebetween thereby reducing the vacuum effect at the inlet end of the cylinder and upon impingement upon the inner wall of the cylinder the globules of the spray further disintegrate to form a mist, the rapidly moving globules of the spray and the mist combining to move a large volume of air through the cylinder.
